(57) **CLAIM**

The ornamental design for a multi-strand fence device, as shown and described.

DESCRIPTION

FIG. 1 is an upper rear left perspective view of a multi-strand fence device showing our new design;

FIG. 2 is a lower front left perspective view thereof;

FIG. 3 is a left side elevation view thereof, the right side elevation view being a mirror image thereto;

FIG. 4 is a rear elevation view thereof;

FIG. 5 is a front elevation view thereof;

FIG. 6 is a top plan view thereof, the bottom plan view being a mirror image thereto; and,

FIG. 7 is an upper rear left perspective view thereof; shown in a position of use with environmental subject matter. The broken lines shown in FIG. 7 depict environmental subject matter that forms no part of the claimed design.
